UNITED STATES PATENT OFFICE.

OZIAS A. SMITH, OF ATLANTA, GEORGIA.

BASEMENT OR CELLAR FLOOR.

SPECIFICATION forming part of Letters Patent No. 274,985, dated April 3, 1883.

Application filed September 4, 1882. (No model.)

To all whom it may concern:

Be it known that I, OZIAS A. SMITH, a citizen of the United States, residing at Atlanta, in the county of Fulton and State of Georgia, have invented a new and useful Improvement in Moisture and Vermin Proof Basement or Cellar Floors; and I do hereby declare that the following is a full, clear, and exact description of the invention, which will enable others skilled in the art to make and use the same.

Heretofore (especially in southern sections) the flooring of basements or cellars was constructed by leveling off the ground and then laying on it sleepers or floor-beams, on which the floor-planks are laid. Floors so constructed soon decay from the ravages of vermin and the action of the moisture, producing rapid decay and rendering the apartment so floored damp and unhealthy and admitting of the passage of vermin into the house.

To carry my invention into effect in a basement or cellar so to be floored, I level off the earth, and, as shown in the accompanying drawing, I lay the sleepers or floor-beams A (which before laying I saturate with crude carbolic acid or creosote-oil, to prevent decay) on the earth B, securing them in position by means of stakes C driven into the earth under and alongside of the sleepers, preventing them from moving with any settlement of the earth's surface, and then I fill in between and underneath the sleepers or beams with a mastic or

slightly plastic concrete, D, consisting of sand thoroughly intermixed with coal-tar and crude carbolic acid or creosote-oil in the proportions of about forty gallons of tar and six gallons of crude acid to the cubic yard of sand. This concrete is applied when fresh mixed and rammed down solid until its top surface is level with the top of the sleepers, and from the absorption of the carbolic acid or creosote-oil by the sleepers and flooring, thereby increasing the durability of the wood-work, this mastic gradually becomes hard and firm. Then the floor is finished by nailing the planking to the sleepers in the usual manner, the whole operation rendering the floor moisture and vermin proof and vastly more durable than if constructed without the antiseptic coating and filling.

Having thus described my invention, what I claim as new, and desire to secure by Letters Patent, is—

A flanked flooring for basements and cellars, the sleepers or beams of which are coated or saturated, or both, with crude carbolic acid or creosote-oil, and the spaces between filled in with a mastic of coal-tar, creosote-oil, and sand or equivalent material, substantially as set forth, and for the purposes described.

OZIAS A. SMITH.
